CLAIM

The ornamental design for a curved electronic gaming machine display, as shown and described.

DESCRIPTION

FIG. 1 is a perspective view of the curved electronic gaming machine display showing our new design;
FIG. 2 is a front elevational view of the curved electronic gaming machine display of FIG. 1;
FIG. 3 is a rear elevational view of the curved electronic gaming machine display of FIG. 1;
FIG. 4 is a right side elevational view of the curved electronic gaming machine display of FIG. 1;
FIG. 5 is a left side elevational view of the curved electronic gaming machine display of FIG. 1;
FIG. 6 is a top plan view of the curved electronic gaming machine display of FIG. 1; and
FIG. 7 is a bottom plan view of the curved electronic gaming machine display of FIG. 1;
FIG. 8 is a perspective view of a first alternative embodiment of the curved electronic gaming machine display of our new design;
FIG. 9 is a front elevational view of the first alternative embodiment of the curved electronic gaming machine display of FIG. 8;
FIG. 10 is a rear elevational view of the first alternative embodiment of the curved electronic gaming machine display of FIG. 8;
FIG. 11 is a right side elevational view of the first alternative embodiment of the curved electronic gaming machine display of FIG. 8;
FIG. 12 is a left side elevational view of the first alternative embodiment of the curved electronic gaming machine display of FIG. 8;
FIG. 13 is a top plan view of the first alternative embodiment of the curved electronic gaming machine display of FIG. 8; and
FIG. 14 is a bottom plan view of the first alternative embodiment curved electronic gaming machine display of FIG. 8.
FIG. 15 is a perspective view of a second alternative embodiment of the curved electronic gaming machine display of our new design;

FIG. 16 is a front elevational view of the second alternative embodiment of the curved electronic gaming machine display of FIG. 15;

FIG. 17 is a rear elevational view of the second alternative embodiment of the curved electronic gaming machine display of FIG. 15;

FIG. 18 is a right side elevational view of the second alternative embodiment of the curved electronic gaming machine display of FIG. 15;

FIG. 19 is a left side elevational view of the second alternative embodiment of the curved electronic gaming machine display of FIG. 15;

FIG. 20 is a top plan view of the second alternative embodiment of the curved electronic gaming machine display of FIG. 15; and

FIG. 21 is a bottom plan view of the second alternative embodiment of the curved electronic gaming machine display of FIG. 15.

FIG. 22 is a perspective view of a third alternative embodiment of the curved electronic gaming machine display of our new design;

FIG. 23 is a front elevational view of the third alternative embodiment of the curved electronic gaming machine display of FIG. 22;

FIG. 24 is a rear elevational view of the third alternative embodiment of the curved electronic gaming machine display of FIG. 22;

FIG. 25 is a right side elevational view of the third alternative embodiment of the curved electronic gaming machine display of FIG. 22;

FIG. 26 is a left side elevational view of the third alternative embodiment of the curved electronic gaming machine display of FIG. 22;

FIG. 27 is a top plan view of the third alternative embodiment of the curved electronic gaming machine display of FIG. 22; and

FIG. 28 is a bottom plan view of the third alternative embodiment of the curved electronic gaming machine display of FIG. 22.

FIG. 29 is a perspective view of a fourth alternative embodiment of the curved electronic gaming machine display of our new design;

FIG. 30 is a front elevational view of the fourth alternative embodiment of the curved electronic gaming machine display of FIG. 29;

FIG. 31 is a rear elevational view of the fourth alternative embodiment of the curved electronic gaming machine display of FIG. 29;

FIG. 32 is a right side elevational view of the fourth alternative embodiment of the curved electronic gaming machine display of FIG. 29;

FIG. 33 is a left side elevational view of the fourth alternative embodiment of the curved electronic gaming machine display of FIG. 29;

FIG. 34 is a top plan view of the fourth alternative embodiment of the curved electronic gaming machine display of FIG. 29; and,

FIG. 35 is a bottom plan view of the fourth alternative embodiment of the curved electronic gaming machine display of FIG. 29.

In the drawings, the broken lines depict environmental subject matter only and form no part of the claimed design.
